UNITED STATES PATENT OFFICE.

GIUSEPPE F. PINSUTI, OF NEW YORK, N. Y.

NON-REFILLABLE BOTTLE.

1,139,446.

Specification of Letters Patent.

Patented May 11, 1915.

Application filed May 1, 1912. Serial No. 694,446.

To all whom it may concern:

Be it known that I, GIUSEPPE F. PINSUTI, a citizen of the United States, residing at the borough of Manhattan, city, county, and State of New York, have invented a new and useful Improvement in Non-Refillable Bottles, of which the following is a specification.

My present invention relates to a non-refillable bottle, and the object thereof is the provision of a bottle stopper of sufficiently low cost of production to be practical, and which is readily placed in position in the neck of the bottle, and by the use of which the bottle is made substantially non-refillable.

In carrying out my invention, I employ a stopper, adapted to fit within the neck of the bottle, the stopper being provided with a transverse recess and a port communicating from the inner end of the stopper and the transverse recess, and also with longitudinal surface recesses providing for communication between the other or outer end of the stopper, and a recess formed by a rib in the neck of the bottle, a valve controller fitting and longitudinally movable within the said transverse recess of the stopper, means for normally maintaining the valve controller in position, a valve intermediate of the said valve controller and the seat, which is movable independently of the valve controller in attempts to refill the bottle, and means for securing the stopper within the neck of a bottle, all of which will be hereinafter more particularly described.

In the drawing, Figure 1 is a central longitudinal cross section of the neck of the bottle fitted with my improved stopper. Fig. 2 is a view similar to Fig. 1 taken at right angles thereto. Fig. 3 is a transverse cross section on line $\alpha\alpha$ Fig. 1. Fig. 4 is a transverse cross section on line $\gamma\gamma$ Fig. 1, and Fig. 5 is a transverse cross section on lines $\alpha\alpha$ Fig. 1, and Fig. 6 is a side elevation of my improved stopper.

Referring to the drawing, 10 indicates the neck of a bottle, which in any suitable position is provided with a circumferential rib 11, providing for the interior recess 12. Fitted within the neck of the bottle, I employ a stopper indicated at 13. This stopper is preferably a one-piece structure, and in spaced positions in its surface I provide recesses to receive cork rings 14. As indicated in the drawing, I preferably employ

two of these cork rings, and surrounding the cork rings and the body of the stopper, I also employ a cylinder of celluloid, indicated at 15. The outer surface of the celluloid cylinder forms a contact with the inner surface of the neck of the bottle, and the cork rings form a more or less yielding support to the celluloid cylinder.

In the body of the stopper is a transverse recess 16, and from the inner end of the stopper there is a conically shaped port leading into the transverse recess 16, by means of which port, as will be understood, communication is provided from the interior of the bottle to the recess 16. A wall forming the inner surface of the recess 16 constitutes a valve seat 18. Within the transverse recess 16, I employ the valve controller indicated at 19. The extreme length of this valve controller is substantially the diameter of the stopper, and at the opposite ends of the valve controller, running longitudinally thereof and preferably placed centrally, there are ribs 20, provided on either side thereof with recesses 21.

Between the upper end of the valve controller 19 and the adjacent wall, or that forming the top or roof of the recess 16, I employ a spring 22, the function of which, as will be understood, is to maintain the valve in its normal position.

Between the valve controller 19 and the valve seat 18, I employ a valve 23, which is preferably an imperforate gasket of thin rubber or other flexible material. As plainly shown in Fig. 5, the length of this valve is practically the same as the length of the valve controller 19, which is that of the diameter of the stopper. At its ends, 95 the valve 23 is recessed or cut away, as indicated at 24. These recessed portions of the valve are of considerably less extent than the same portions of the valve controller 19, so that parts of the valve, with which no contact is made by the valve controller 19, extend over the valve seat.

In the surface of the stopper, I employ recesses 25-26. The recess 25 is preferably V-shaped in cross section and provides communication between the mouth of the bottle neck and the recess 12 for the flow of the liquid in emptying the bottle, and the recess 26 makes a like communication for the purpose of admitting air into the bottle as its liquid contents are discharged.

As will be understood, when the bottle is

inverted, to empty the same, the weight of the valve controller 19, together with the pressure of the liquid contents of the bottle, causes the valve controller 19 to move, compressing the spring 22. The flow of the contents of the bottle also causes the valve 23 to move with the valve controller, and the bottle is emptied by its contents passing through the ports 17, the recess 19, or those portions thereof not occupied by the valve and valve controller, to the recess 12, and passes through the recess 25 to the mouth of the bottle. The strength of the spring 22 is amply sufficient to return the valve controller, as well as the valve, to their normal positions when the bottle is placed in a substantially horizontal position. It is not believed to be practical, however, to make this spring of any greater strength, and the purpose of employing the valve, constructed as hereinbefore described, is to prevent attempts at refilling the bottle when inverted and placed at an angle to the horizontal. In this event, while the valve controller 19 remains open, the liquid, with which the bottle may be attempted to be refilled, would flow through the recesses 21 and come into contact with those portions 24 of the valve extending beyond the confines of the recesses 21, and this valve is so light that the flow of the liquid striking these portions 24 thereof, would carry it to its seat and prevent any material quantity of liquid entering the bottle.

35 I claim as my invention:

1. A non-refillable bottle, a stopper having a chamber therein, ports providing communication between the chamber and the opposite ends of the stopper, a member 40 slidable within the said chamber, there being provided recesses forming ports for the passage of liquid by the said slidable member, a valve seat, and a valve of light flexible and yielding material fitting loosely within the said chamber and adapted to be normally maintained against its seat by the said slidable member, and to be returned to its seat, independently of the said slidable member, by liquid flowing into the bottle through the stopper.

50 2. In a non-refillable bottle, a stopper having a transverse chamber therein opening in the side of the stopper, a port providing communication between the inner 55 end of the stopper and the said chamber, a valve of flexible material provided with recesses in the corners thereof, a seat for the valve and a device within the said chamber adapted to normally maintain the valve against its seat, the said device being provided with recesses in the corners thereof which are relatively deeper than the recesses in the corners of the valve so that in an attempt to refill the bottle the liquid may 60 be brought directly into contact with the

face of the valve, and means for normally maintaining the said device against the valve to keep the same on its seat.

3. In a non-refillable bottle, a stopper having a transverse chamber therein opening in the side of the stopper and a port providing communication between the inner end of the stopper and the said chamber and longitudinal recesses in the surface of the said stopper providing communication between the outer end of the stopper and a recess formed in the neck of the bottle, which latter recess is in communication with the said chamber, a valve of light flexible yielding material, a valve seat therefor, and a device within the said chamber adapted to normally maintain the valve against its seat, the said valve being adapted to seat independently of the said device in an attempt to refill the bottle.

4. In a non-refillable bottle, a stopper having a chamber therein opening in the side of the stopper, and a port providing communication between the said chamber and the inner end of the stopper, a valve of light flexible and yielding material, the edges thereof at the corners being recessed, and a device within the said chamber adapted to normally maintain the valve against its seat, the said device being provided at its corners with recesses which at the surface of the device contacting with the valve, are relatively deeper than the recesses in the corners of the valve, so that in an attempt to refill the bottle the pressure of the liquid will be brought to bear directly upon the surface of the valve.

5. In a non-refillable bottle, a one-piece stopper having a transverse chamber therein opening in the side of the stopper, a port providing communication between the inner end of the stopper and the said chamber, and longitudinal recesses in the surface of the stopper providing communication between the outer end of the stopper and a recess formed in the neck of the bottle, which latter recess is in communication with the said chamber, a valve seat in the inner end of the said chamber, a valve of light flexible and yielding material, and a device within the said chamber adapted to normally maintain the valve against its seat, the contact surface of the said device with the valve being of materially less area than the area of the valve.

6. In a non-refillable bottle, a one-piece stopper having a transverse chamber therein, opening in the side of the stopper, and a port providing communication between the inner end of the stopper and the said chamber, and longitudinal recesses in the surface of the stopper providing communication between the outer end of the stopper and a recess formed in the neck of the bottle, which latter recess is in communication

with the said chamber, a valve seat at the inner end of said chamber, and a valve of light flexible yielding material adapted to bear against the valve seat.

- 5 7. In a non-refillable bottle, a stopper having a chamber therein, ports providing communication between the chamber and the opposite ends of the stopper, a member 10 provided recesses forming ports for the passage of liquid around the said slidale member, a valve seat, and a valve of light flexible material fitting loosely within the said

chamber, the surface of the said valve being continuous and the area thereof greater than the contact surface between the same and the adjacent face of the said slidale member so that liquid flowing into the bottle through the stopper strikes portions of the said valve to carry the same to its seat independently of the said slidale member.

Signed by me this 24th day of April, 1912.

GIUSEPPE F. PINSUTI.
